Florance McAuliff

By *Florance McAuliff*,
Attorney

UNITED STATES PATENT OFFICE.

FLORANCE MC AULIFF, OF MANDAN, NORTH DAKOTA.

ROTARY SCREEN CLEANER FOR CONICAL AND CYLINDRICAL SCREENS.

Application filed October 3, 1927. Serial No. 223,692.

The present invention relates to a rotary screen cleaner for conical and cylindrical screens and aims to provide a device which will prevent the clogging up of interstices of 5 a foraminous rotary screen such as are used in apparatus for cleaning and assorting gravel, rock, and the like.

An important object of the invention resides in the provision of a screen cleaner of 10 this nature which is simple in its construction, inexpensive to manufacture, strong and durable, thoroughly efficient and reliable in operation, and otherwise well adapted to the purpose for which it is designed.

15 With the above and numerous other objects in view as will appear as the description proceeds, the invention resides in certain novel features of construction, and in the combination and arrangement of parts as will 20 be hereinafter more fully described and claimed.

In the drawings:—

Figure 1 is a fragmentary side elevation of the frame of a machine on which are mounted 25 rotary screens showing one of my cleaners in position,

Figure 2 is a top plan view thereof,

Figure 3 is an end elevation partly in section of one of the cleaners, and,

30 Figure 4 is a fragmentary longitudinal section through one end of the cleaner.

Referring to the drawing in detail, it will be seen that the numeral 5 denotes the frame structure of a gravel and sand washing plant 35 with a rotary conical screen 6 mounted therein in the usual well known manner. I provide a pair of standards 7 rising from the frame 5 and having mounted on their upper ends a hinge pin 8. A pair of arms 9 have hinge 40 straps 10 rotatably engaged on the hinge pin 8 and these arms are braced in respect to each other by cross braces 11. Bearings 12 are carried by the arms and have rotatable therein a shaft 14 on which my improved rotary 45 cleaner is mounted. This cleaner comprises a drum 15 of sheet metal rolled so as to be circular in cross section as is clearly indicated in Figure 4, the longitudinal ends being bent inwardly as at 16 and secured together and 50 the transverse ends being bent inwardly to form annular flanges 17. Spiders 18 have their ends secured to the flanges 17 and are

fixed to the shaft 14 by means of set screws 15 or in any other suitable manner, the spiders being provided with collars or sleeves 19 through which the shaft 14 extends and in which the said screws 15 are mounted. The drum may be of suitable formation and is shown herein by way of example as of a frusto-conical formation so as to operate with 55 a frusto-conical screen, but of course, may be cylindrical to conform properly with a cylindrical screen. The roller bears against the screen of its own weight and may be readily swung out of the way as will be readily apparent. This roller cleaner is run by the force of the screen when the same is in rotation since it rests thereon and the result is that this roller will keep the screen clean at 60 all times.

70 Heretofore these screens have required the constant attention of a man or men to keep them open, that is, the irregularities of coarse sizes of rock, gravel, and the like, cause the various rock or the like to become clogged in 75 the screen with the result that unless they are constantly attended to the screen will become clogged and of course, cease to properly function, but with the use of the roller cleaners this will be obviated. The structure of the 80 cleaner is extremely simple as will be quite apparent and will operate without any attention.

The present embodiment of the invention 85 has been disclosed in detail since in actual practice it attains the features of advantage enumerated as desirable in the statement of the invention and the above description. It will be apparent that changes in the details of construction, and in the combination and arrangement of parts may be resorted to without departing from the spirit and scope 90 of the invention as hereinafter claimed or sacrificing any of its advantages.

Having thus described my invention, what 95 I claim as new is:—

1. A screen cleaner of the class described comprising a shaft, a pair of sleeves on the shaft, spider structures on the sleeves, a sheet of metal disposed concentrically about the shaft having its longitudinal edges curved inwardly and fixed together so that the sheet 100 is circular in cross section, the ends of the sheet being bent inwardly to provide flanges

which are fixed to the ends of the spider structure.

2. A screen cleaner of the class described, comprising a sheet of metal bent in tubular formation and having its longitudinal edges curved inwardly and fixed together, so that the sheet is circular in cross section, the edge

of the sheet being bent inwardly to provide flanges, a shaft extending through the tubular sheet, and means connecting the shaft 10 with the end flanges.

In testimony whereof I affix my signature.

FLORANCE McAULIFF.
